[57] **CLAIM**

The ornamental design for a planter, substantially as
shown and described.

DESCRIPTION

FIG. 1 is a reduced perspective view of a planter showing
my new design.

FIG. 2 is a side elevational view taken from the right of
FIG. 1;

FIG. 3 is a side elevational view taken from the left of
FIG. 1;

FIG. 4 is a top plan view. The bottom is unornamented.
The supporting cord has been omitted in FIGS. 2
through 4 for ease of illustration.
